DUAL HEAD FOR A SQUARE

Peter Andrews, 190 Gebhardt Road, Penfield, N.Y.

Filed Jan. 19, 1959, Ser. No. 54,216

Term of patent 14 years

(Cl. D52—6)

FIG. 4

FIG. 2

FIG. 5

FIG. 3

Fig. 1 is a top plan view of dual-head for a square, showing my new design.

Fig. 2 is a side elevational view thereof.

Fig. 3 is a bottom view thereof.

Fig. 4 is a front elevational view thereof.

Fig. 5 is a rear elevational view thereof.

The undisclosed side of the dual-head is the same in appearance as the side shown except for the omission of the D-border in the lower part of said head.

I claim:

The ornamental design for a dual-head for a square, substantially as shown and described.
